UNITED STATES PATENT OFFICE

156,472

COMBINED CANDELABRA AND FLOWER HOLDER

Ernst J. Wolter, Chicago, Ill.

Application December 20, 1948, Serial No. 150,285

Term of patent 14 years

(Cl. D48—2)

To all whom it may concern:

Be it known that I, Ernst J. Wolter, a citizen of the United States, residing at Chicago, in the county of Cook and State of Illinois, have invented a new, original, and ornamental Design for a Combined Candelabra and Flower Holder, of which the following is a specification, reference being had to the accompanying drawing, forming a part thereof.

Fig. 1 is a top plan view of a combined candelabra and flower holder showing my new design;

Fig. 2 is a front view; and

Fig. 3 is a side view.

I claim:

The ornamental design for a combined candelabra and flower holder, substantially as shown.
ERNST J. WOLTER.
